Primary Examiner — John A Voytek(74) *Attorney, Agent, or Firm* — MALLOY & MALLOY, PL(57) **CLAIM**

The ornamental design for a tire tread as shown and described.

DESCRIPTION

FIG. 1 is a perspective view illustrating my design for a tire tread;

FIG. 2 is a front view thereof;

FIG. 3 is a top view thereof;

FIG. 4 is a right side view thereof;

FIG. 5 is a left side view thereof;

FIG. 6 is a rear view thereof; and,

FIG. 7 is a bottom view thereof.

The broken lines in the drawings are for illustrative purposes only and form no part of the claimed design.
